UNITED STATES PATENT OFFICE

JOSEPH LAWSON, OF LONDON, ENGLAND, ASSIGNOR TO ASIATIC PETROLEUM COMPANY, LIMITED, OF LONDON, ENGLAND

FLUID-TIGHT MOTION-TRANSMITTING DEVICE

Application filed June 18, 1928, Serial No. 286,478, and in Great Britain June 29, 1927.

This invention relates to improvements in fluid-tight motion transmitting devices, of the kind comprising a flexible tube sealed at one end into or around an aperture formed in a fluid containing chamber and closed at the other end, and is for use with apparatus in which motion is transmitted from a self-contained mechanical unit to a second unit located outside the first mentioned unit, as, for example, in the case where motion is transmitted from a change-over mechanism, for controlling the supply of liquid to a pair of containers, to a mechanism for indicating the quantity of liquid delivered.

The object of the present invention is to provide in apparatus of this kind an arrangement whereby the external unit may be detached from the self-contained unit without affecting the fluid-tight joint and without affecting the operation of the self-contained unit.

According to the present invention the flexible tube seals an aperture formed in the case of the self-contained unit and detachably interconnected means are provided for transmitting the motion between the self-contained and external units.

The detachably interconnected means preferably comprises a rod in engagement at one end with a cap sealing one end of the flexible tube and having at its other end a pin portion adapted to extend within a socket operatively connected to the external unit.

Preferably, in order to increase the flexibility of the tube, it is transversely corrugated.

In the accompanying drawing, Figure 1 is a vertical section illustrating the invention applied to a plug cock; Figure 2 is an elevation, partly in section, looking from the right of Figure 1 and showing the parts constituting the invention and Figure 3 is a diagrammatic view of apparatus wherein the invention is employed.

Referring more particularly to Figure 3, which indicates diagrammatically and conventionally the type of apparatus to which the invention relates, A B are two containers, adapted to be supplied with liquid delivered from a pump C, the supply and discharge of

liquid to and from the containers being controlled by a change over mechanism D. E is an indicating mechanism which is actuated by the operation of the mechanism D and indicates the quantity of liquid delivered.

Referring now to Figures 1 and 2, the said change over mechanism D comprises any known kind of plug cock 1 rotatably mounted in a casing or body 2 having a chamber 3 to which liquid is supplied from the said pump C and from which liquid is delivered under the control of the said plug cock 1 through a passage 4 to the measuring containers in the known manner. 5 is a chamber in which is located any known kind of apparatus for automatically effecting, in known manner, the reversal of the plug cock through engagement with a jaw 7 of the latter when the pressure of the liquid rises due to the filling of a container, the liquid pressure being transmitted from the chamber 3 to the chamber 5 through a passage 6. The end of the plug cock 1 is formed with a cam 8 upon which rests a projection 9 on a sheath 10 having further projections 11 adapted gradually to be engaged by the cam 8.

The lower end of the sheath 10 is formed with a sleeve 12 which receives a cup-shaped member 13 to which is secured, as by soldering, the upper end of a flexible corrugated metallic tube 14, the lower end of which is secured, as by soldering, to a plug 15 bolted on to the casing 2, packing 16 being interposed between said plug and casing.

Extending into a recess formed in the cup-shaped member 13 is the head 17 of a motion transmitting rod 18 which extends with substantial clearance through the tube 14 and is provided with a head 19 extending into a socket formed in a member 20. The member 20 is pivotally mounted on pins 21 which are secured in a plug 22 by means of a split spring ring 23, the lower end of said member 20 extending downwardly to engage mechanism for actuating the aforesaid conventional indicating mechanism E located within a casing 24 to which the plug 22 is secured. It will be seen that the indicating mechanism forms a unit which is external to the plug cock reversing unit.

In operation when the plug cock 1 is reversed, the cam 8 gradually moves into engagement with the projections 11 and thereafter rocks the cam sheath 10 and the rod 18, which latter transmits the motion to the member 20 to actuate the mechanism for actuating the indicating mechanism, the tube 14, by reason of its flexibility, permitting said movement. It will be seen that the head and socket connection 19, 20 permits the external indicating mechanism to be removed without affecting the continued operation of the plug cock if desired, since the aperture in the plug 15 remains sealed by the tube 14 and member 13.

What I claim is:

1. The combination of a self-contained mechanical unit having a body defining a chamber adapted to contain a fluid, a second unit external to said self-contained unit, a flexible tube sealing an aperture in said body and a motion transmitting device comprising detachably interconnected means external to said chamber, for transmitting movement between said self-contained and external units, said device passing through and being secured to said tube.

2. The combination of a self-contained mechanical unit having a body defining a chamber adapted to contain fluid, a second unit external to said self-contained unit, a flexible tube one end of which is secured in an aperture formed in said body, a member secured to and sealing the other end of said tube, said member being in operative relationship with said self-contained mechanical unit, and detachably interconnected means for transmitting motion between said self-contained and external units, said device being in substantial engagement with said member and extending through the open end of said tube.

3. The combination of a self-contained mechanical unit having a body defining a chamber adapted to contain a fluid, a second unit external to said self-contained unit, a flexible tube sealing an aperture in said body, a motion transmitting device for transmitting movement to said external unit and comprising detachably interconnected means external to said chamber, said device passing through and being secured to said tube, a cam sheath in engagement with said motion transmitting device, and a cam operable by the self-contained mechanical unit and adapted progressively to move into contact with said cam sheath.

4. The combination of a self-contained mechanical unit having a body defining a chamber adapted to contain a fluid, a second unit external to said self-contained unit, a flexible tube one end of which is secured in an aperture in said body, a member secured to and sealing the other end of said tube, a cam sheath in engagement with said member,

a cam operable by said self-contained unit and adapted progressively to move into contact with said cam sheath, and detachably interconnected means for transmitting movement to said external unit, said means being in substantial engagement with said member and extending through the open end of said tube.

5. The combination of a self-contained mechanical unit having a body defining a chamber adapted to contain a fluid, a second unit external to said self-contained unit, a flexible tube sealing an aperture in said body and a motion transmitting device comprising a pin and socket connection external to said chamber, for transmitting movement between said self-contained and external units, said device passing through and being secured to said tube.

6. The combination of a self-contained mechanical unit having a body defining a chamber adapted to contain a fluid, a second unit external to said self-contained unit, a flexible tube sealing an aperture in said body, a motion transmitting device for transmitting movement to said external unit and comprising a pin and socket connection external to said chamber, said device passing through and being secured to said tube, a cam sheath in engagement with said motion transmitting device, and a cam operable by the self-contained mechanical unit and adapted progressively to move into contact with said cam sheath.

7. The combination of a self-contained mechanical unit having a body defining a chamber adapted to contain fluid, a second unit external to said self-contained unit, a flexible tube one end of which is secured in an aperture formed in said body, a member secured to and sealing the other end of said tube, said member being in operative relationship with said self-contained mechanical unit, and detachably interconnected means for transmitting motion between said self-contained and external units, said device being in substantial engagement with said member and extending through the open end of said tube, said detachably interconnected means comprising a pin and socket connection.

8. The combination of a self-contained mechanical unit having a body defining a chamber adapted to contain a fluid, a second unit external to said self-contained unit, a flexible tube one end of which is secured in an aperture in said body, a member secured to and sealing the other end of said tube, a cam sheath in engagement with said member, a cam operable by said self-contained unit and adapted progressively to move into contact with said cam sheath, and detachably interconnected means for transmitting movement to said external unit, said means being in substantial engagement with said member and extending through the open end

of said tube, said detachably interconnected means comprising a pin and socket connection.

9. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible tube sealing an aperture in said body, and a motion transmitting device for transmitting movement from said control means to said indicating mechanism, and comprising detachably interconnected means external to said chamber, said device passing through and being secured to said tube.

10. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible tube one end of which is secured in an aperture formed in the body, a member secured to and sealing the other end of said tube, said member being in operative relationship with said control means, and detachably interconnected means for transmitting motion between said control means and said indicating mechanism, said means being in substantial engagement with said member and extending through the open end of said tube.

11. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible tube sealing an aperture in said body, a motion transmitting device for transmitting movement to said indicating mechanism and comprising detachably interconnected means external to said chamber, said device extending into said chamber, and being secured to said tube, a cam sheath in engagement with said motion transmitting device, and a cam operable by said control means and adapted progressively to move into contact with said cam sheath.

12. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating

mechanism, a flexible tube one end of which is secured in an aperture in said body, a member secured to and sealing the other end of said tube, a cam sheath in engagement with said member, a cam operable by the control means and adapted progressively to move into contact with said cam sheath, and detachably interconnected means for transmitting movement to said indicating mechanism, said means being in substantial engagement with said member and extending through the open end of said tube.

13. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible tube sealing an aperture in said body, and a motion transmitting device for transmitting movement from said control means to said indicating mechanism, and comprising a pin and socket connection external to said chamber, said device passing through and being secured to said tube.

14. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible tube sealing an aperture in said body, a motion transmitting device for transmitting movement to said indicating mechanism and comprising a pin and socket connection, external to said chamber, said device extending into said chamber and being secured to said tube, a cam sheath in engagement with said motion transmitting device, and a cam operable by said control means and adapted progressively to move into contact with said cam sheath.

15. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible tube one end of which is secured in an aperture formed in the body, a member secured to and sealing the other end of said tube, said member being in operative relationship with said control means, and detachably interconnected means for transmitting motion between said control means and said indicating mechanism, said means being in substantial engagement with said member and extending through the open end of said tube, said detachably interconnected

means comprising a pin and socket connection.

16. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible tube one end of which is secured in an aperture in said body, a member secured to and sealing the other end of said tube, a cam sheath in engagement with said member, a cam operable by the control means and adapted progressively to move into contact with said cam sheath, and detachably interconnected means for transmitting movement to said indicating mechanism, said means being in substantial engagement with said member and extending through the open end of said tube, said detachably interconnected means comprising a pin and socket connection.

17. The combination of a self-contained mechanical unit having a body defining a chamber adapted to contain a fluid, a second unit external to said self-contained unit, a flexible, metallic, transversely corrugated tube sealing an aperture in said body and a motion transmitting device comprising detachably interconnected means external to said chamber, for transmitting movement between said self-contained and external units, said device passing through and being secured to said tube.

18. The combination of a self-contained mechanical unit having a body defining a chamber adapted to contain fluid, a second unit external to said self-contained unit, a flexible, metallic, transversely corrugated tube one end of which is secured in an aperture formed in said body, a member secured to and sealing the other end of said tube, said member being in operative relationship with said self-contained mechanical unit, and detachably interconnected means for transmitting motion between said self-contained and external units, said device being in substantial engagement with said member and extending through the open end of said tube.

19. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible, metallic, transversely corrugated tube sealing an aperture in said body, and a motion transmitting device for transmitting movement from said control means to said indicating mechanism, and comprising detachably interconnected means

external to said chamber, said device passing through and being secured to said tube.

20. The combination of a pair of measuring containers, a self-contained mechanical unit comprising means for controlling the supply and discharge of liquid to and from said containers, said unit having a body providing a chamber adapted to contain the liquid, a second unit external to said self-contained unit and comprising an indicating mechanism, a flexible, metallic, transversely corrugated tube one end of which is secured in an aperture formed in the body, a member secured to and sealing the other end of said tube, said member being in operative relationship with said control means, and detachably interconnected means for transmitting motion between said control means and said indicating mechanism, said means being in substantial engagement with said member and extending through the open end of said tube.

In testimony that I claim the foregoing as my invention I have signed my name this first day of June, 1928.

JOSEPH LAWSON.
